UNITED STATES PATENT OFFICE.

HENRY H. TAYLOR, OF BRIDGEPORT, CONNECTICUT.

POMPADOUR-ROLL.

No. 882,655.

Specification of Letters Patent. Patented March 24, 1908.

Application filed November 6, 1907. Serial No. 401,009.

To all whom it may concern:

Be it known that I, HENRY H. TAYLOR, a citizen of the United States, residing at Bridgeport, in the county of Fairfield and State of Connecticut, have invented certain new and useful Improvements in Pompadour-Rolls; and I do hereby declare the following to be a full, clear, and exact description of the invention, such as will enable others skilled in the art to which it appertains to make and use the same.

My invention relates to certain improvements in "pompadour rolls" such as are used by women for the purpose of producing a certain effect in the arrangement of the hair, and consists of the construction and arrangement hereinafter fully described and then particularly pointed out in the claims which concludes this application.

In the accompanying drawing, which forms a part of this application—Figure 1 is a plan view of a wire mesh blank such as is employed in the manufacture of my improvement—Fig. 2 a plan view showing the edges of this blank slightly contracted to throw up the central portion of the blank into the required degree of fullness—Fig. 3 a view similar to Fig. 2 but showing the contracted edges bound with a substance, like stiff paper, to cover the raw edges of the wires—Fig. 4 a view similar to Fig. 3 but showing the edges bound with a suitable tape placed over the paper and stitched therethrough, while the ends and sides of the device are provided with suitable eyelets—Fig. 5 a side elevation of the construction shown at Fig. 4—Fig. 6 a back view of the construction shown at Fig. 4, and Fig. 7 a cross section.

Similar numbers of reference denote like parts in the several figures of the drawing.

Heretofore bustles have been made from a woven wire blank cut on the bias, with the wire edges contracted to throw up the proper fullness or bulge effect in the body of the bustle, the edges of the wires being subsequently bound to clamp the same and preserve this effect, attention in this respect being called to U. S. Letters Patent No. 617,452, issued January 10, 1899, to this applicant jointly with M. B. Hammond.

The present invention differs from a bustle in that great care is taken to cover the edges of the wires so that they will be soft and flexible and will not injure the scalp, while the

roll itself is provided at the sides and ends with eyelets through which hairpins may be inserted for the purpose of keeping the device in position upon the head of the wearer; also, a backing is used which not only affords a cushion against the head of the wearer, but is so secured to the edges of the roll that the back of the latter is drawn to the proper shape and the device itself rendered firm.

1 represents the woven wire blank cut on the bias from which the roll is made, 2 the paper strip which is bound around the edges of the blank after said edges have been contracted to give the proper fullness to the body of the roll, 3 is the backing which is preferably made of cloth the edges of which are assembled beneath the paper binder, the sides of the roll being slightly contracted so that when the binder and the backing are stitched in position the latter will be taut, 4 is the tape which is bound around the edges of the roll over the paper binding, and 5 the eyelets which are inserted at the sides and at the ends of the completed roll.

The device will retain its shape permanently for the reason that the backing is secured to the edges of the roll at a tension, and this backing at the same time affords a yielding cushion which renders the device very comfortable to the head of the wearer.

It will be observed that the bound edges of the roll extend considerably beyond the plane of the backing and in angular disposition thereto, and the object of this is to afford a soft resilient seat for the roll. Fig. 7 has been drawn on an enlarged scale and special prominence has been given to the bound edge in order that the fact may be appreciated that this edge will spread and have a resilient action.

What I claim as new and desire to secure by Letters Patent is:—

1. A pompadour roll comprising a body portion made from a woven wire blank cut on the bias, the edges of said blank being contracted to give the required fullness to said body, a backing secured at a tension to the rear portion of the contracted body by means of a paper binder stitched around said edges, a tape bound around said edges outside of the paper binder, said bound edges being soft and flexible and extending beyond the plane of said backing, and eyelets set within the roll at the ends and the sides thereof.

2. A device of the character described,

consisting of a body portion made from a woven wire blank cut on the bias, the edges of which are contracted to produce the required fullness to said body, a soft flexible binding around the edges of said body portion, a flexible backing secured at a tension to the rear of said body portion in a plane inside that of the bound edges, and eyelets set

within these bound edges at the sides and ends of the device.

16

In testimony whereof I affix my signature in presence of two witnesses.

HENRY H. TAYLOR.
